CAR CONSTRUCTION

Alfred C. Schmohl, Beaver Falls, Pa., assignor to
Pressed Steel Car Company, Inc., Pittsburgh,
Pa., a corporation of Pennsylvania

Application July 15, 1939, Serial No. 284,667

4 Claims. (Cl. 105—280)

My invention pertains to highway and rail vehicles having lading bodies, the side walls of which are formed of doors hinged adjacent the floor thereof and opening outwardly and downwardly to discharge lading. My invention pertains particularly to a combination stake and lock for retaining the doors in upright closed position and locking same against accidental displacement.

10 An object of the invention is to provide a collapsible door-stake which, when in operative position, retains the door in closed position and supports same from the car underframe.

Another object of the invention is to provide a collapsible stake which may be readily released from locked position so that the door will move by gravity from closed to open position.

Another object of the invention is to provide a combined door-stake and lock of the character described which may be easily and safely operated, thereby avoiding endangering the operator.

A further object of the invention is to provide the combined stake and lock herein described with a safety device which positively prevents accidental displacement and which must be released before releasing the door lock.

Referring now to the drawing forming part of this specification wherein Fig. 1 shows in elevation a portion of the side of a vehicle body equipped with the invention; Fig. 2 is a section taken along lines 2—2 of Fig. 1, showing the collapsible stake and lock in position to retain the door in upright closed position; and Fig. 3, showing a section through the car similar to that illustrated in Fig. 2 but with the stake in collapsed position; the vehicle body comprises side sills 1, a floor 2, and side walls formed of doors 3 pivotaly mounted adjacent the floor of the body on hinges 4. These doors 3 may be of any suitable construction and of wood or steel.

In the drawing the doors 3 are illustrated as comprising longitudinally disposed wooden planks secured together by braces 6 and having the top and side edges bound by metal strips 7 and 8, respectively. A side wall of the car may comprise one or more doors, depending upon design requirements. The door-stake of the invention is comprised of two parts, one part being rigidly secured to the door and serving as a part of the hinge support for the door on the body, the other part being hinged to the door and engaging the underframe.

As shown in the drawing the part rigidly secured to the door comprises angularly shaped members 9 arranged in pairs adjacent the ends

of the door with one flange 9a secured to the door by means of bolts 10, and flanges 9b extending outwardly from the door; the flanges 9b being spaced apart longitudinally of the door for purpose hereinafter described. Each member 9 has a downwardly extending portion 9c terminating adjacent the hinge 4 and having a suitable aperture therein for reception of a hinge pin 11 securing the extension 9c to the hinge 4 and upon which the door rotates in moving from closed to open position.

The other portion of the door stake, which contributes to the support of the door in closed position and which is pivotally mounted upon the portion of the door stake rigidly secured to the body, comprises spaced apart pairs of members 12 disposed vertically of the door and extending downwardly beneath the hinge 4 to a bearing on the sill 1. The upper portions of the members 12 are connected by the member 13 disposed between and connecting the members 12 by means of suitable fastening members 14. The member 13 is offset adjacent the free end thereof and extends between the members 9, the free end of the member 13 having a suitable aperture therein for reception of the hinge pin 15 pivotally connecting the member 13 to the flanges 9b of the members 9. The bottom portion of the members 12 are preferably connected by means of the member 16.

For the purpose of retaining the members 12 in position to support the door a suitable latch is pivotally mounted between the members 12 on pin 17. Said latch is provided with a depending handle portion 18 and a hook-shaped portion 19 extending between the spaced flanges 9b of the members 9 and engaging pin 20 which connects the flanges 9b. This handle portion 18 may be of sufficient weight to normally move portion 19 to a position for automatically engaging pin 20 when the door 3 is returned to closed position. For this purpose the outer portion of hook 19 may be shaped so as to rotate the latch to depress hook 19 upon engagement with pin 20. After hook 19 moves beneath the pin 20, during return of the door 3 to closed position, the weight of handle 18 causes a gravitational rotation of the latch to engage hook 19 with pin 20. In order to prevent the latch from rotating beyond a position facilitating the performance of this function, pin 32 is provided on member 12 to engage hook 19 and restrict movement of the latch in released position. Whilst the handle portion 18 will normally retain the latch in engagement with pin 20, in order to prevent accidental displacement of

the latch I provide chain 21, having one end connected by means of bracket 22 to the car body and the other end of the chain being provided with an open ended hook 23 engaging a suitable aperture 24 in the handle 18 of the latch.

5 In order to prevent the members 12 from engaging the ground or other obstructions, and to prevent injury thereto when the door is opened, I provide a suitable collapsible link comprising 10 members 25 and 25^a, one end of the members 25 and 25^a being pivotally connected together by means of the pin 26, the opposite end of the member 25 being pivotally connected by means of the pin 27 to the flanges 9^b of the members 9 15 and the free end of the member 25^a being pivotally connected to the members 12 by means of pin 28.

In order to prevent the door from striking side sill 1 of the body when the door is moved into 20 open position and to prevent damage to the door and sill, I provide a suitable spring buffering bar 29 which is secured by means of fastening members 30 to the sill 1. This member 29 depends below the sill 1 as shown in Figs. 1 and 3. A suitable buffering pad 31 is secured to the door 3 and engages the spring buffering bar 29 when the door is moved to open position.

Referring now to Figs. 2 and 3 of the drawing, wherein the door is shown in closed and open 30 position respectively. When the door is in closed position as shown in Fig. 2 and the latch engaged with the pin 20, the door stake members 12 engage the side sill member 1 to retain the door 3 in closed position. The hook 23 of the 35 chain 21 engaging the latch handle 18 prevents accidental release of the latch from the pin 20 and thus securely holds the door in closed position. When it is desired to release the door 3 for opening, the operator releases the hook 23 from the latch handle 18 and thereafter moves the 40 latch handle 18 into the position shown in dot and dash lines on Fig. 2, thereby releasing the latch from the pin 20 and the door 3 is free to open by gravity. As the door moves from the 45 position shown in Fig. 2 to that shown in Fig. 3, the buffering pad 31 on the door engages the spring buffer bar 29 and prevents injury to the door. The jointed link 25 permits limited outward movement of the members 12 away from the door and causes the members 12 to move inwardly 50 under the side of the car and beneath the car floor 2 so that the door stake in released position does not at any time depend below the lower edge of the door 3 when in open position.

55 As illustrated in Fig. 1 of the drawing, the door stakes are preferably located adjacent each end of the door so that with an operator standing at each door stake may release the latches from the pins 20 and readily move out of the way of the opening door. Likewise with this arrangement each door, regardless of size, can be released by the operators while standing a safe distance from the door. In the latter case the operators first release the chains 21 from the handles 18 60 of the latches and then by means of a hook bar or other instruments releases the latches from the pin 20 permitting the door 3 to open by gravity.

When it is desired to move the doors from open 70 to closed position the procedure is reversed; the door is first moved from position shown in Fig. 3 to that shown in Fig. 2. During this movement of the door, the members 12 will fall by gravity into position against the sill 1 and, if not, may 75 be manually so moved and thereafter the latch

moved to engage pin 20, thereby securing the door in closed position. The safety chain and hook may then be engaged with the latch handle 18 as shown in Fig. 2.

Having thus described the invention what I 5 claim as new and desire to secure by Letters Patent is:

1. In a vehicle, in combination, a body, a door forming a side wall of the body and hinged thereto for movement into a position below the floor 10 thereof, a locking member extending on opposite sides of the horizontal plane of said hinge, a permanent pivotal connection between the upper end of said member and the door, a bearing on a fixed portion of said vehicle for the lower end 15 of said member, an independently movable latch for retaining said member in fixed relation to said door and vehicle, a stop limiting relative movement between the member and door, and buffering means on said vehicle engaging said door when 20 in position below the floor of the body.

2. In a car body, in combination, a lading supporting floor, a side sill beneath one edge of the floor, a door forming a portion of the body side wall and hinged to said side sill for opening 25 downwardly below the horizontal plane of said lading floor, a pair of vertically disposed spaced angle members each having one leg secured to the outer face of the door above said sill and the other leg extending outwardly from the door, a 30 second pair of angle shaped members disposed outwardly of said first named pair and extending parallel thereto above and below said floor, a pivotal connection between the upper portions of said pairs of angle members, means connecting 35 said pairs of angle members intermediate the ends thereof to limit relative movement between said pairs of angle members, a latch pivotally mounted between said second named pair of angle members and comprising a depending handle portion 40 and an upwardly extending hook shaped portion adapted to be disposed between the first named pairs of angle members, a pin connecting the outwardly extending legs of the first named pair of angle members and in position to be engaged 45 by the hook extending portion of the latch to retain the pairs of angle shaped members in fixed relative position, and suitably shaped end portions on the lower ends of said pair of angles engaging the side sill to lock the door in closed position 50 when the said latch is engaged with said pin.

3. In a car body, in combination, a lading supporting floor, a door forming a portion of the body side wall and hinged to the body below the horizontal plane of said floor for opening 55 outwardly and downwardly below said plane, a locking member having its upper end pivoted to said door and its lower end adapted to releasably engage the body below said door hinges, collapsible means permanently engaging the locking member and door limiting relative pivotal movement between the said member and door when the door depends below the floor in open position, a keeper on said door, a latch pivoted to said locking member and provided with a depending portion at one side of said latch pivot and an upwardly extending portion at the other side thereof for engaging the door keeper, and means on said locking member limiting rotation of the latch in an unlocking direction. 70

4. In a vehicle body including a floor and a door hinged to the body to form a portion of the body side wall when in raised position, a mechanism for retaining said door in raised position comprising a rigid member disposed vertically of 75

the body side wall and extending on opposite sides of the bottom edge of said door in position to engage the door and the body beneath said door, a pivotal connection between one end of the member and said door to support the member in said vertical position and upon which support the member pivots freely away from the door and body as the door is lowered to discharge lading, a latch pivotally mounted on said rigid member and having an upwardly extending hook shaped portion disposed toward said door, said latch having the preponderance of its weight disposed on a side of its pivotal support opposite to

that of said hook shaped portion, and a keeper on said door beneath which said hook shaped latch portion may be moved to prevent rotation of the said rigid member relative to said door after the latter is moved from lowered to raised position, said hook shaped portion of the latch having a suitably shaped end portion for engaging and moving downwardly across said keeper as the said pivoted member falls by gravity against the raised door and causing rotation of the latch into a position for gravitational movement beneath said keeper. 5 20
